UNITED STATES PATENT OFFICE.

WILLIAM H. MINER, OF CHICAGO, ILLINOIS.

BUFFER DEVICE FOR RAILWAY-CARS.

1,152,035.

Specification of Letters Patent. Patented Aug. 31, 1915.

Application filed December 1, 1913. Serial No. 803,903.

To all whom it may concern:

Be it known that I, WILLIAM H. MINER, a citizen of the United States, residing at Chicago, in the county of Cook and State of Illinois, have invented a certain new and useful Improvement in Buffer Devices for Railway-Cars, of which the following is a full, clear, concise, and exact description, reference being had to the accompanying drawings, forming a part of this specification.

My invention relates to improvements in buffer devices for railway cars.

The object of my invention is to provide a buffer having means to insure the quick and ready action of the parts supported by the face plate of a railroad car, and to keep the meeting face plates between cars together under the varying conditions obtaining in the practical operation of railroad cars.

In the drawings forming a part of this specification—Figure 1 is a plan view partly in horizontal section of a buffering device for railroad cars embodying my invention; Fig. 2 is an elevation partly in vertical longitudinal section of the centrally located members of the buffering device; Fig. 3 is a side elevation partly in longitudinal vertical section of one of the side members of the buffering device showing the side stem thereof; Fig. 4 is a cross section taken on line 4—4 of Fig. 1; Fig. 5 is a perspective view of one of the rolls showing the bearing axle assembled therewith; Fig. 6 is a perspective view of one of the bearings for the rolls; Fig. 7 is a perspective view of one of the rolls with its axle removed; Fig. 8 is a perspective view of a modified form of bearing for the rolls.

Referring to the drawings the numeral 9 represents the platform of a passenger car provided with a pocket 10 for receiving the central compression resisting members of the buffering device 11. The central compression resisting member 11 consists of a shell 12 containing friction mechanism 13; a buffer cap 14 adapted to engage the wedge stem 15 and the preliminary spring 16, which is seated around the said wedge stem.

The foregoing parts of the central buffering member may be of any suitable construction.

The numeral 17 represents the central buffer stem engaging at its rear end the central buffering member and at its forward end the rear face 18 of the face plate 19, which in usual construction comprises the rear member 20 and the front member 21.

The numeral 22 represents the front platform end sill or buffer beam.

In preferable construction the buffering device is provided with side members 23, 23, 60 there being one at either side of the central buffering member, each of substantially the same construction, which consists of a side stem 24, the side stems 24, 24, and the center stem 17, each passing through the buffer beam or platform end sill 22 through suitable apertures 25, 25 and 26, 26 provided in the front and rear portions thereof respectively. The buffer beam 22 is provided with a plurality of hollow chambers 27, 27, 27, 70 each of said chambers being adapted to receive a buffer stem therethrough. The side stems are each preferably rectangular or square in cross section in the forward portion thereof, the rearward portion thereof 7 being preferably cylindrical in form or circular in cross section. The rear portion of each side stem is provided at its rear end with a spring seat 28, a nut 29, and preferably with a cotter pin 30 to secure the nut 80 against accidental displacement. Adjacent the rear face of the buffer beam each side stem is provided with a spring seat 31 against which is seated at its forward end the side stem spring 32, the said side stem spring 85 engaging at its rear end the spring seat 28.

The side walls of each chamber 27 in the buffer beam are formed by plates 34, 34 extended transversely of the beam and preferably integral therewith. Each of said chambers is provided with bottom rollers 35, preferably two in number, each of said rollers being adapted to engage the buffer stem passing through the chamber. Each of said rollers comprises a roll 36, preferably cylindrical 95 in form, with a trunnion 37 extended from either end thereof. The trunnion 37 preferably consists of the ends of an axle 38 passed through the opening 39 in the roller. One desirable way of making the rollers is to 100 provide the axle 38 and cast the roll 36 about the same. Each of the bottom rollers is journaled in a bearing 40, the said bearing being preferably a block-like member in shape with vertical end faces 41, 41, and provided with a lug 42 on its bottom surface, each of said bearings being mounted upon a spring 43 seated at its lower end against the bottom wall 44 of a chamber 27, and at its upper end about the lug 42.

A vertical way 45 is provided in each chamber for the bearing 40, and in prefer-

able construction the ends 41 of the bearing 40 are adapted to engage against the sides 46, 46 of the way 45. The chambers through which the side stems are passed are provided 5 with upper rollers, preferably one for each chamber. Each of the upper rollers preferably comprises a cylinder 47 having an axle 48 passing therethrough, and extending at either end through a perforation 49 provided 10 in the adjacent plates 34. Each axle 48 has a head 50 at one end and a cotter pin 51 at its other end to guard against accidental displacement. The forward end of each side stem engages the face plate by means of an 15 annular pin 52 with which the side stem is provided, the said pin being received within a strap 53 secured to the face plate.

In the modification of bearing for the rollers shown in Fig. 8 of the drawings the 20 numeral 55 represents a block-like bearing member provided with a plurality of recesses 56, 56, each to receive a trunnion of a roll, and also provided with a plurality of lugs 57, 57 around each of which the ends 25 of a spring may be seated. If this form of bearing is employed the same is disposed within a chamber 27 in the buffer beam, the ways 45 hereinbefore described may be dispensed with, and the bearing 55 mounted 30 in the single way formed by the ends of a chamber 27.

It will be understood that the face plate 20 engages a similar face plate upon the next adjacent car in a train of cars. The face 35 plate in usual car construction is required to support other heavy parts of the car vestibule including the heavy vestibule face plates. It is important that the face plates herein described and the vestibule 40 face plates borne by the same upon one car be kept in constant contact with the face plates of the adjacent railroad car in a train to prevent injury to those passing from one car to another by obviating the danger of 45 being caught between vestibule face plates, or the face plates 20 described herein, should

the same become separated. Heretofore upon wearing of the buffer stems and a consequent distortion in the shape thereof it has happened that the buffer has not quickly 50 operated to hold the face plates of adjoining cars together on sudden movements of the train, such as a jerk thereof. It will be obvious that my invention insures not only a means of preventing wear of the buffer 55 stems, but also insures a minimum vertical clearance of the buffer stems within the buffer beam at all times during the life of the car, and thus not only insures a ready response of the parts in sudden relative 60 movements of the cars of the trains, but also insures the constant engagement of the face and vestibule plates of one car with the face and vestibule plates of another car, and further results in the prevention of the rattling 65 in car vestibules that has heretofore been constant in the operation of trains when the buffer stems become even slightly worn.

I claim:—

1. In a buffer for railway cars, the combination with a buffer beam and buffer stem, of anti-friction rollers between which said stem is mounted, the rollers being placed above and below said stem and the lower rollers having extended trunnions at the 75 ends thereof, separate slidable bearings for said trunnions at each end of the rollers, and springs beneath said bearings.

2. In a buffer for railway cars, the combination with a buffer beam and buffer stem, 80 of anti-friction rollers between which said stem is mounted, some of said rollers having extended trunnions at the ends thereof, bearings for said trunnions at the ends of the rollers, and springs supporting said bearings, said buffer beam being provided with integral guideways in which said bearings are mounted.

WILLIAM H. MINER.
